UNITED STATES PATENT OFFICE.

GEORGE L. SCOVILLE, OF WEST SUPERIOR, WISCONSIN, ASSIGNOR, BY DIRECT AND MESNE ASSIGNMENTS, OF THREE-FOURTHS TO EDA A. SCOVILLE, ANDREW H. SCOTT, AND CHARLES A. WARD, OF SAME PLACE.

WEATHER-STRIP.

SPECIFICATION forming part of Letters Patent No. 639,831, dated December 26, 1899.

Application filed December 1, 1898. Serial No. 698,035. (No model.)

To all whom it may concern:

Be it known that I, GEORGE L. SCOVILLE, a citizen of the United States, residing at West Superior, in the county of Douglas and State 5 of Wisconsin, have invented a new and useful Weather-Strip, of which the following is a specification.

My invention relates to improvements in weather-strips of that class wherein a slidable strip is fitted in the recess in the bottom edge of the door to dispense with a threshold-strip on the door-sill; and the purpose of the present improvement is to simplify the construction and render the device efficient and reliable in operation, so that on the closing of the door the strip is positively depressed into firm engagement with the door-sill to exclude the weather.

A further purpose of the invention is to provide means by which the slidable strip is depressed positively on closing the door, and such depressing means may be adjusted to regulate the extent of adjustment of the weather-strip to compensate for shrinking of 25 the door and of the sill, and thereby effect nicety in the adjustment of the strip, so as to secure proper closure of the space between the door and the sill.

With these ends in view the invention consists in the novel combination of elements and in the construction and arrangement of parts, which will be hereinafter fully described and claimed.

To enable others to understand the invention, I have illustrated the preferred embodiment thereof in the accompanying drawings, forming a part of this specification, and in which—

Figure 1 is a perspective view with the door partly open and showing my improved weather-strip applied thereto. Fig. 2 is a vertical sectional view in the plane of the jamb and the door, showing the latter closed. Fig. 3 is a vertical transverse section on the plane indicated by the dotted line 3 3 of Fig. 2. Fig. 4 is a detail perspective view of the slidable strip with the springs attached thereto. Fig. 5 is a detail sectional elevation of the bumper.

Like numerals of reference denote like and corresponding parts in each of the several figures of the drawings.

10 designates the door-jamb, which is provided with the usual internal bead or shoulder 11, against which the door 12 may press or bear when it is closed, the door being hinged 55 at 13 to the jamb. All of these parts are ordinary in the art, and no novelty therefor is herein claimed.

To accommodate the slidable weather-strip, a recess or channel 14 is cut in the lower edge 60 of the door 12, and in said recess is snugly fitted a slidable strip 15, which may be made of any suitable material. This strip 15 is suspended or hung within the recessed lower edge of the door by springs, which serve to 65 actuate the strip, thereby dispensing with means for guiding the strip in its proper play or for connecting the strip to the door other than by the springs. The strip 15 is capable of a vertical play or movement simultaneous 70 with its endwise movement, and the suspension-springs are arranged to give the proper travel to the strip when the door is opened, so that the lower edge of the strip will lie practically flush with the corresponding edge 75 of the door when the latter is opened. The strip is provided with a series of inclined slots in its upper edge, and in the drawings I have represented the slidable strip as provided with two slots 16 17, which are arranged 80 near the respective ends of the strip and are inclined in the same or corresponding directions. Each inclined slot is provided with a long face 18 and a short side 19, and each slot terminates at its lower end in a rounded 85 enlargement or eye 20.

The suspension and actuating springs for the slidable strip are indicated by the numerals 21 21, and these springs are inclined to properly fit the slots 16 17. Each spring 90 21 consists of a flat piece of elastic metal, which is provided at its lower end with a rounded or spirally-bent journal 22 and with a flat head 23. The journal 22 of the spring is made by coiling or twisting the lower end 95 of said spring upon itself, and the flat head 23 of the spring lies at an angle to the inclined spring-shank. The springs are secured within the recess of the door by fitting the flat heads 23 thereof against the lower horizontal face of the door-recess and by passing the screws 24 through the spring-heads 23, so

that the upper ends of the springs are fastened securely to the door. The inclined shanks of the springs pass through the inclined slots of the strip, and the round journals 22 are fitted snugly in the rounded eyes 20 of said strip. The diameters of the eyes 20 in the strip and the journals 22 of the springs exceed the width of the slots at the lower ends thereof contiguous to the enlargements 10 or eyes 20, and this construction prevents the journals 22 of the springs from pulling out of the slots in the strip. The springs and strip are thus connected for the strip to be carried or sustained wholly by the springs, and the 15 latter serve to raise the strip when the door is opened for the lower edge of the strip to lie practically flush to the corresponding edge of the door. The springs, with their upper ends fastened firmly within the recess of the 20 door, are adapted to have their free ends move or travel in an arc of a circle in order to impart an endwise movement to the strip simultaneously with its vertical movement, and as the springs are fixed at one end their 25 twisted journals 22 are adapted to turn slightly in the enlargements or eyes of the strip-slots without, however, exposing the parts to disconnection one from the other.

In my improved weather-strip the construction is such that it is necessary to make a single recess in the lower edge of the door, such recess extending practically the full width of the door and being of uniform size in cross-section, the lower edge of the door 35 within the recess lying in a plane parallel with the exposed edge of said door. This construction simplifies the formation of the door for the reception of the strip and facilitates the attachment of the springs, because 40 it is only necessary to fasten one end of each spring directly to a straight top wall of the recess in the door. Each spring is made from a single piece of resilient sheet metal and is bent to form a rounded journal at one end 45 and the shank at the other end, that portion of the spring between the shank and the journal being inclined in order to suspend the weather-strip below the door and to permit said strip to have the necessary vertical play. 50 From the foregoing description it will be understood that the springs on opening the door move the slidable strip endwise, so as to project its inner end beyond the hinged edge of the door, and to effect the depression 55 of the strip 15 when the door is closed I employ a bumper 25, which is attached to the door-jamb in a position to lie in the path of the slidable strip. This bumper consists of a strip or length of spring metal having a 60 slot or fork 26 at one end, and said bumper-spring is arranged in a vertical position on the door-jamb to have its upper end fastened securely thereto by a screw 27, which passes through a suitable opening in said bumper-spring and is embedded in the jamb. The 65 lower forked end of the bumper-spring receives an antifriction-roller 28, which is jour-

naled loosely, as at 29, in the free end of said spring, and this roller is adapted to ride against the end of the slidable strip 15, thus 70 reducing the friction between the bumper-spring and the end of the slidable strip. To prevent the bumper-spring from yielding unduly under the impact or pressure of the spring-controlled strip 15, I employ an adjustable stop-screw 30, which is secured in the door-jamb at a point between the fastening-screw 27 and the friction-roller 28. This stop-screw offers resistance to the inward movement of the bumper-spring under the 80 pressure of the strip 15 when the door is closed, and said screw 30 may be adjusted more or less in relation to the bumper-spring to project the latter at variable distances from the face of the door-jamb, whereby the bumper 85 may be adjusted to depress the strip 15 more or less, and thus secure nicety of adjustment of the spring-pressed strip, so as to compensate for shrinkage of the door or sill and effect the tight closing of the space between 90 the door and sill by the weather-strip. The head of the stop-screw 30 is accessible through an opening 31, which is formed in the bumper-spring to permit the operator to introduce the point of a screw-driver or other implement 95 for engagement with the screw to adjust the latter; but the diameter of this opening 31 is less than the width of the screw-head in order that the latter may have proper bearing against the bumper-spring to offer resistance 100 to the inward movement of the bumper when the slidable strip presses against the friction-roller, which is carried by the bumper-spring.

Changes may be made in the form of some of the parts while their essential features are 105 retained and the spirit of the invention embodied. Hence I do not desire to be limited to the precise form of all the parts as shown, reserving the right to vary therefrom.

Having thus described the invention, what 110 I claim is—

The combination with a door, a recessed jamb, an endwise-movable strip confined slidably on said door and springs connecting the strip to the door, of a slotted bumper-spring 115 attached to said jamb and having its free end extended into the recess thereof, a roller mounted in said free end of the bumper-spring and arranged in position to ride against the end of said movable strip on closure of 120 the door, and an adjusting-screw fixed to the jamb and bearing against the bumper-spring to adjust the friction-roller relative to the path of the movable strip, said screw being accessible, for adjustment thereof, through 125 the slot in the bumper-spring, as set forth.

In testimony that I claim the foregoing as my own I have hereto affixed my signature in the presence of two witnesses.

GEORGE L. SCOVILLE.
